US00D918886S

(12) **United States Design Patent** (10) Patent No.: **US D918,886 S**
Song et al. (45) Date of Patent: ** *May 11, 2021

(54) **MOBILE PHONE**(71) Applicant: **Samsung Electronics Co., Ltd.**, Suwon-si (KR)(72) Inventors: **Sanghoon Song**, Gumi-si (KR); **Youn-Gun Jung**, Suwon-si (KR); **Yoonyoung Choi**, Seoul (KR); **Junyoung Lee**, Seoul (KR)(73) Assignee: **SAMSUNG ELECTRONICS CO., LTD.**, Suwon-si (KR)

(*) Notice: This patent is subject to a terminal disclaimer.

(**) Term: **15 Years**(21) Appl. No.: **29/712,052**(22) Filed: **Nov. 5, 2019**

CLAIM

The ornamental design for a mobile phone, as shown and described.

DESCRIPTION

FIG. 1 is a front perspective view of a mobile phone showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is a rear perspective view thereof.

The broken lines in the drawings illustrate portions of the mobile phone that form no part of the claimed design.
